(57) CLAIM

The ornamental design for a pillow case, as shown and described.

DESCRIPTION

FIG. 1 is a perspective view of a pillow case showing our new design;

FIG. 2 is a right-side view of the pillow case;

FIG. 3 is a front view of the pillow case;

FIG. 4 is a top view of the pillow case;

FIG. 5 is a rear view of the pillow case;

FIG. 6 is a left-side view of the pillow case;

FIG. 7 is a bottom side view of the pillow case;

FIG. 8 is a perspective view of the pillow case, with the L-shaped zipper open; and,

FIG. 9 is a perspective view of the double pillow contained in the pillow case.

The broken lines shown are for illustrative purposes only and form no part of the claimed design.
